J. D. PEDERSEN.

FIREARMS

APPLICATION FILED DEC. 24, 1919.

1,410,268.

Patented Mar. 21, 1922.

UNITED STATES PATENT OFFICE.

JOHN D. PEDERSEN, OF JACKSON, WYOMING.

FIREARM.

1,410,268.

Specification of Letters Patent. Patented Mar. 21, 1922.

Application filed December 24, 1919. Serial No. 347,074.

To all whom it may concern:

Be it known that I, JOHN D. PEDERSEN, a citizen of the United States, residing in Jackson, in the county of Lincoln and State 5 of Wyoming, have invented certain new and useful Improvements in Firearms, of which the following is a specification.

This invention relates more especially to that class of firearms usually designated as 10 small arms, and a principal object of the invention is to furnish an improved firing train mechanism and grip-safety device particularly applicable to auto-loading and automatic pistols.

15 One class of small arms to which my present improvements are applicable includes the auto-loading pistols having a grip-stock or handle portion which is adapted to receive a safety device operable by hand-grip or compression.

An improved auto-loading pistol of this kind is described in my Patent No. 1,348,733, dated August 3, 1920, and granted on my copending (renewal) application, Serial 25 No. 311,689, filed July 17th, 1919. Therefore, for convenience of illustration, I have herein shown my present improvements as arranged and applied to the particular kind 30 of auto-loading pistol shown in the drawings of said patent, to which reference may be had.

The features of my firing train mechanism and grip-safety device are that it is a firing train mechanism and a grip or handle contained safety device arranged to prevent firing of the firearm by locking the firing member or hammer and the trigger sear when the grip-operable or grip-safety member of my invention is in normal or safety position.

35 Also, when the firearm is provided with a main slide comprising a firing-pin, to prevent discharge of the firearm by locking the main slide of the firearm to prevent effective contact between the firing-pin and the cartridge, so that action of the firing member 40 or hammer on the cartridge will not explode the cartridge.

Another feature of my invention is that it is a firing train mechanism and grip-safety device so organized as to effect the locking of the main slide in forward position by means of a combined rockable slide-detainer and controller which engages a face 45 on the main slide that is rearward of the

block-abutment face of the frame of the fire- 55 arm for retarding the breech-block in its rearward action.

In this manner I secure the advantage of a more rigid form of breech-block than is shown in either my said patent or my co-pending application Serial No. 345,550, filed December 17, 1919, and I further secure a breech-block by which the firing-pin is entirely carried.

Another feature of my invention is, that a 65 means for blocking the rockable slide-detainer and controller in position for locking the main slide, and for blocking the sear-member in position for locking the firing member in firing position is provided, which 70 blocking means is moved to blocking position when the grip-operable or grip-safety member of my invention is non-compressed or in normal or safety position, and which blocking means is moved out of blocking position by engagement therewith of the grip-operable or grip-safety member when the grip-operable or grip-safety member is grip-compressed. 75

Another feature of my invention is, that 80 when the firing member or hammer is moved to firing position and the grip-operable or grip-safety member is moved to position of safety, the rockable slide-detainer and controller is moved to locking position, or upwardly as shown, by means carried by the grip-operable or grip-safety member, and the sear member is moved to lock the firing member or hammer in firing position by a similar means. 85

Another feature of my invention is that the slide-detainer and controller is moved to unlocking position, that is downwardly as shown, when the firing member or hammer is moved from firing position to fired 95 position, by contact or engagement of the trigger member with the slide-detainer and controller.

Still another feature of my invention is that a swinging sear member is provided to 100 lock the firing member or hammer in firing position, which swinging sear member is of arm form pivotally supported at a longitudinal end thereof and engageable at the other longitudinal end thereof with the 105 trigger member.

In the accompanying drawings which illustrate an embodiment of my invention,—

Figure 1 is a side view, partly broken away to show the details, of a pistol provided with my firing train mechanism and grip-safety device, the trigger sear and firing member or hammer being locked in firing position and the main slide locked against rearward movement by the slide-detainer and controller, the grip-operable or grip-safety member of my invention being 10 in normal or safety position.

Fig. 2 is a fragmentary detail side view on larger scale than Fig. 1, of the rear end and grip-stock of a pistol provided with my firing train mechanism and grip-safety device, the main slide of the pistol being 15 locked by the slide-detainer and controller, and the trigger sear and firing member or hammer being locked in firing position by the slide-detainer and controller, the means 20 for blocking the slide-detainer and controller or blocking member being moved by grip-compression of the grip-operable or grip-safety member, to position for permitting movement of the slide-detainer and controller to unlocking position.

Fig. 3 is a fragmentary detail view, on substantially the same scale as Fig. 2, of a pistol provided with my firing train mechanism and grip-safety device, the slide-detainer and controller being in unlocking position, the firing member or hammer in fired position, and the grip-operable or grip-safety member being grip-compressed.

Fig. 4 is a sectional view on the line 4—4 of Fig. 2, looking in the direction of the arrow, a portion of the grip-stock and some of the parts of my invention being removed.

Fig. 5 is a sectional view on the line 5—5 of Fig. 3, looking in the direction of the arrow, the rear end of the main slide and the grip-operable or grip-safety member being removed.

Fig. 6 is a sectional view on the line 6—6 of Fig. 1, showing the means on the main-slide for guiding the firing pin.

Fig. 7 is a sectional view of the main slide of a pistol, showing the firing member or hammer of my invention being moved to firing or cocked position by rearward movement of the main-slide, and the breech block or breech-bolt of my invention in changed or upward position and moving rearwardly with the main-slide, the firing pin being in raised position in the means 55 on the main-slide for guiding the firing pin.

Similar reference characters or numerals refer to similar parts throughout the several views.

The pistol in the present embodiment of 60 my invention is provided with the main-slide C, and with the rigid breech-block E wholly carrying the firing-pin P, the main-slide C having a guiding means or forked lug or projection C' for the firing-pin P.

which also affords an abutment for the end of the spring 15^a of the firing-pin P. The force of the powder gases is first exerted upon the breech-block E to move it rearwardly, and is transmitted by the breech-block, without the use of any spring or yielding device, to the main-slide C to move the main-slide rearwardly. The breechblock E, Figs. 1, 2 and 3, being in engagement with the slide C at the upper rear end of the 75 breechblock, when moved by powder gases transmits initial rearward movement to the slide, and changes position or rises by engagement of the face 5^b thereof with the face 2^c of the frame, during which period there 80 is retardation of the breechblock relative to the slide, as during engagement of the face 3^b and face 5^d, while the slide moves rearwardly and the face 5^b of the breechblock clearing the face 2^c of the frame the breechblock is locked to the slide, as shown in Fig. 7, and moves concurrently rearwardly therewith until the slide reaches its most retracted position. Forward movement of the slide returns the breechblock to the position 90 shown in Figs. 1, 2 and 3.

The firing member or hammer H is pivotally supported on the frame or grip-stock of the pistol and is movable to firing position and to fired position. The firing member or hammer H is moved from fired position to firing position or cocked position by engagement or contact of the roller 3^e of the main-slide C with the forward face of the firing member or hammer H, as the 100 main-slide is moved rearwardly to its most rearward position; or the firing member or hammer may be moved to firing position or cocked by a suitable face on the main-slide 105 which engages the firing member or hammer when the main-slide is moved to rearward position.

The firing member or hammer H is provided with a firing notch or cock-notch 8^f, and with an eccentric cam face 8^g, the grip-stock of the pistol being bored out or otherwise suitably cut away, as at 2^h to receive the firing member or hammer and the various parts of my invention.

The sear member S is pivotally supported 115 on the grip-stock of the pistol and is a swinging sear member, preferably of the arm shape shown in the drawings, pivoted at a longitudinal end thereof for swinging movement and engageable at the other longitudinal end thereof with the trigger member. The sear member S is provided with a locking shoulder 17^b which is engageable with the cock-notch 8^f of the firing member or hammer H and with a face 17ⁿ which is 125 engageable with the eccentric cam face 8^g of the firing member or hammer, and with an end-face 17^d, which is engageable with the trigger member and the blocking member hereinafter described.

The rocking slide-detainer and controller N is pivotally supported on the grip-stock adjacent to the sear member S and is of crank-form, preferably the substantially 5 bell-crank form shown in the drawings, the upper crank end being guided by a face on the grip-stock and engageable with the rear-face 10 of the main-slide C, and prevented from too great upward movement by a stop- 10 face 11, or other suitable means on the main-slide C. The rocking slide-detainer and controller N is provided with an end-face 14^e, which is engageable with the trigger member and with the blocking member here- 15 inafter described.

The blocking member 12 comprises block- 20 portions 13 and 13', Fig. 5, pivotally supported on the grip-stock, the purpose of the blocking member 12 being to block the rock- 25 ing slide-detainer and controller N in locking or upward position, and to block the sear member S in position for locking the firing member or hammer H in firing position. A spring operated actuator 14 is provided for 30 the block-portion 13, and a similar spring operated actuator 14' is provided for the block-portion 13'. Each spring actuator comprises a spring 15 or 15' and a projector or nose-piece 16 or 16', outwardly pressed 35 or forced by the spring 15 or 15', and engaging the grip-operable or grip-safety member G to hold the blocking member 12 in a position substantially at a right angle to the grip-operable or grip-safety member 40 G, when the grip-operable or grip-safety member is non-compressed or in position of safety, and each block-portion 13 or 13' is provided with an upward extension or point 17 or 17' with which the grip-oper- 45 able or grip-safety member engages as hereinafter described. Each block-portion is provided with a front-face 18 or 18', the front-face 18' being engageable with the sear member S and the front-face 18 being engageable with the rocking slide-detainer 50 and controller N, when the blocking member 12 is in said substantially right angle position.

The grip-operable or grip-safety member 55 G is pivotally connected at its lower end to the grip-stock of the pistol, preferably in the manner described, and set forth in my said patent, and is engageable at its upper end with the frame or receiver B, when non- 60 compressed or in position of safety, the grip-operable or grip-safety member G being yieldable or hand compressible and closing the space 2^s formed in the grip-stock. The grip-operable or grip-safety member G is provided with a transverse projection or transverse rib 19 which engages both the points 17 and 17' of the blocking member 12, to move the blocking member 12, when the grip-operable or grip-safety mem- 65 ber is grip-compressed, out of position for blocking the rocking slide-detainer and controller N and the sear member S. Actuators 20 and 20', Fig. 5, are carried by the grip-operable or grip-safety member G, the actuators being duplicate springs, the actuator 70 20 being seated in the grip-operable or grip-safety member G and received in the sear member S, the tendency of the actuator 20 being to move or force the sear member S into locking engagement with the firing- 75 member H and into position for engagement by the trigger member F, and the actuator 20' being seated in the grip-operable or grip-safety member G adjacently to the actuator 20, and received in the slide-detainer and controller N, the tendency of the actuator 20', being to move the upper end, or crank end, of the slide-detainer and controller when the grip-operable member G is in position of safety, into position for locking 80 the main slide, or upwardly, and to move the lower end of the slide-detainer and controller into position for engagement by the trigger-member S.

The spring 8^e is operatively connected to 90 the grip-operable or grip-safety member G at its lower end and abuts a plunger 8^e which is carried by the grip-operable or grip-safety member, which plunger also provides a seat for the lower end of the connecting rod 8^b which is pivotally attached at its upper end to the firing member or hammer H, the purpose of the spring 8^e being to move the firing member or hammer to fired position, and to afford grip-compression of 100 the grip-operable or grip-safety member, and to return the grip-operable or grip-safety member to position of safety after grip-compression. The construction and arrangement of the spring 8^e, plunger 8^e and 105 rod 8^b is preferably the same as the construction and arrangement of these parts described and shown in my said copending application, Serial No. 311,689 filed July 17th, 110 1919.

The trigger member F is movable forwardly by means not shown, and by pull thereon is movable rearwardly. The trigger member F is received in an opening or slot 21 in the grip-stock of the pistol, the opening or slot 21 being of such length as to allow considerable play or movement of the trigger member downwardly and upwardly. The trigger member F is provided with an end-face 22 which is intended to engage or 120 contact with the end-face 14^e of the rocking slide-detainer and controller N, and is provided with a mortise recess 23 having a face 24 which is intended to engage or contact with the end-face 17^e of the sear member S, the arrangement being such that the end-face 22 will first engage or contact with the end-face 14^e of the slide-detainer and controller N to move the slide-detainer and controller, and that the face 24 will subse- 125 130

4
quently engage or contact with the end-face 17^a of the sear member S to move the sear member.

The actuator 25, is mounted or suitably arranged on the grip-stock of the pistol, which actuator comprises a spring 26, and a projector or nose-piece 27, the tendency of the spring 26 being to force or push the projector or nose-piece against the under edge of the trigger member F to move the trigger member upwardly in the opening or slot 21.

The curved arm 28, is pivotally attached at its upper end to the firing member or hammer H, and the lower end of the arm 28 engages the upper edge of the trigger member F, the purpose of the arm 28 being to move the trigger-member downwardly in the opening or slot 21 when the firing member or hammer is moved from firing position to fired position.

The pin 29, or other suitable means, mounted on the grip-stock of the pistol, provides a guide for the arm 28 in its movement and also provides a stop means or detent means to limit the upward movement of the trigger-member when moved by the actuator 25.

In operation, the firing member or hammer H being in firing position and the grip-operable or grip-safety member G being in position of safety, and the rocking slide-detainer and controller N being blocked in upward locking position, and the sear member S being blocked in position for locking the sear member and firing member or hammer in firing position, Fig. 1, grip-compression of the grip-safety member G moves the blocking-member 12 out of position for blocking the rocking slide-detainer and controller N and the sear member S, and permits movement of the slide-detainer and controller and the sear member, Fig. 2. Pull on the trigger member F first engages or brings into contact the end-face 22 with the end-face 14^a of the rocking slide-detainer and controller N, and rocks or moves the upper end or crank end thereof downwardly to unlocking position, Fig. 3. The same pull on the trigger member F subsequently engages or brings into contact the face 24 of the trigger member F with the end-face 17^a of the swinging sear member S and moves or swings the sear member downwardly out of engagement with the firing member or hammer H, and the firing member or hammer is moved by the spring 8^a to fired position and the pistol is discharged.

As the firing member or hammer H is moved from firing position to fired position the arm 28 engages or bears down upon the upper edge of the trigger member F and forces the end of the trigger member downwardly in the opening or slot 21 against the compression of the actuator 25, and thereby

provides clearance or space to permit upward swinging movement of the sear member S and upward movement of the lower end of the rocking slide-detainer and controller N.

As the firing member or hammer H is moved from fired position to firing or cocked position and grip-compression of the grip-operable or grip-safety member G is released, and this member returns to position of safety, the pressure of the arm 28 on the trigger member F is relieved and the trigger member is moved upwardly in the slot 21 to its first position by the actuator 25; the rocking slide-detainer and controller N is rocked or moved upwardly by the actuator 20' into position for locking the main-slide C against rearward movement, and the swinging sear member is moved or swung upwardly by the actuator 20 to lock the firing member or hammer H in firing position, while the blocking member 12 through pressure of the actuating springs 13 and 13', as the grip-operable or grip-safety member G is moved to position of safety, is moved into position for blocking the sear member in said locking position, and for blocking the rocking slide-detainer and controller N in its locking position.

Having thus described my invention, I claim:

1. In a firearm, in combination, a frame of said firearm, a main slide movable rearwardly and forwardly on said frame, and provided with a rear-face, and comprising a firing-pin, a firing member movable to firing position by rearward movement of said main slide and movable to fired position, and engageable with said firing-pin, rockable means engageable with said rear-face of the main slide to lock the main slide against rearward movement, sear means engageable with said firing member, a grip-compressible member engageable with said frame when in position of safety, and releasable from said engagement by grip-compression, means carried by said grip-compressible member for moving said rockable means to said locking position when said firing member is moved to firing position, and for moving said sear means to lock said firing member in firing position, means engaging said grip-compressible member for blocking said rockable means and sear means in said locking positions when said grip-compressible member is in position of safety, and movable from said blocking position by grip-compression of the grip-compressible member, spring means for moving said firing member to fired position, and trigger means first engageable when said grip-compressible member is grip-compressed, with said rockable means to move the same to unlocking position, and subsequently engageable with said sear means to release said firing mem- 130

ber for movement to fired position, by one pull on the trigger means.

2. In a firearm, in combination, a frame of said firearm, a main slide movable rearwardly and forwardly on said frame and provided with a rear-face and comprising a firing-pin, a firing member movable to firing position by rearward movement of said main slide and movable to fired position and engageable with said firing-pin, rockable means engageable with said rear-face of the main slide to lock the main slide against rearward movement, sear means engageable with said firing member, a grip-operable member engageable with said frame when in position of safety and releasable from said engagement by grip-compression, means carried by said grip-operable member for moving said rockable means to said locking position when said firing member is moved to firing position, and for moving said sear means to lock said firing member in firing position, means engaging said grip-operable member for blocking said rockable means and sear means in said locking positions when said grip-operable member is in position of safety and said firing member is in firing position, and movable from said blocking position by grip-compression of the grip-operable member, means for moving said firing member to fired position, and affording grip-compression of the grip-operable member for returning the grip-operable member to position of safety after release of said trigger means.

3. In a firearm, in combination, a frame of said firearm, a main slide movable rearwardly and forwardly on said frame and provided with a rear-face and comprising a firing-pin, a firing member movable to firing position by rearward movement of said main slide and movable to fired position and engageable with said firing-pin, rockable means engageable with said rear-face of the main slide to lock the main slide against rearward movement, sear means pivotally supported at a longitudinal end thereof and engageable with said firing member by swinging movement, a grip-operable member engageable with said frame when in position of safety and releasable from said engagement by grip-compression, means carried by said grip-operable member for moving said rockable means to said locking position when said firing member is moved to firing position, and for moving said sear means to lock said firing member in firing position, means engaging said grip-operable member for blocking said rockable means and sear means in said locking positions when said grip-operable member is in position of safety and said firing member is in firing position, and movable from said blocking position by grip-compression of the grip-operable member, means for moving said firing member to fired position, and affording grip-compression of the grip-operable member for returning the grip-operable member to position of safety after release of said trigger means.

member for blocking said rockable means and sear means in said locking positions when said grip-operable member is in position of safety, and movable from said blocking position by grip-compression of the grip-operable member, spring means for moving said firing member to fired position, and affording grip-compression of the grip-operable member, and for returning the grip-operable member to position of safety after grip-compression, and trigger means first engageable, when said grip-operable member is grip-compressed, with said rockable means to move the same to unlocking position, and subsequently engageable with said sear means to release said firing member for movement to fired position, by one pull on said trigger means.

4. In a firearm, in combination, a frame of said firearm, a main slide movable rearwardly and forwardly on said frame and provided with a rear-face, and comprising a firing-pin, a firing member movable to firing position by rearward movement of said main slide and movable to fired position and engageable with said firing pin, rockable means engageable with said rear-face of the main slide to lock the main slide against rearward movement, sear means pivotally supported at a longitudinal end thereof and engageable with said firing member by swinging movement, a grip-operable member engageable with said frame when in position of safety and releasable from said engagement by grip-compression, spring means carried by said grip-operable member for moving said rockable means to said locking position when said firing member is moved to firing position, and for moving said sear means to lock said firing member in firing position, means engaging said grip-operable member for blocking said rockable means and sear means in said locking positions when said grip-operable member is in position of safety, and movable from said blocking position by grip-compression of the grip-operable member, spring means for moving said firing member to fired position, and affording grip-compression of the grip-operable member, and for returning the grip-operable member to position of safety after grip-compression, trigger means first engageable, when said grip-operable member is grip-compressed, with said rockable means to move the same to unlocking position, and subsequently engageable with said sear means to release said firing member for movement to fired position, by one pull on said trigger means, means actuated by said firing member when the same is moved to fired position to move said trigger means to prevent interference thereof with said rockable means and sear means when said firing member is moved to firing position, and spring means for mov-

ing said trigger means to normal position when said firing member is moved to firing position.

5. In a firearm, in combination, a frame of said firearm, a main slide movable rearwardly and forwardly on said frame and provided with a rear-face, a breech-block movable with said main slide and comprising a firing pin, a firing member movable to firing position by rearward movement of said main slide and movable to fired position and engageable with said firing pin, rockable means engageable with said rear-face of the main slide to lock the main slide against rearward movement, sear means engageable with said firing member, a grip-operable member engageable with said frame when in position of safety, and releasable from said engagement by grip-compression, means carried by said grip-operable member for moving said rockable means to said locking position when said firing member is moved to firing position, and for moving said sear means to lock said firing member in firing position, means engaging said grip-operable member for blocking said rockable means and sear means in said locking positions when said grip-operable member is in position of safety and said firing member is in firing position, and movable from said blocking position by grip-compression of the grip-operable member, spring means for moving said firing member to fired position and affording grip-compression of the grip-operable member, and for returning the grip-operable member to position of safety after grip-compression, and trigger means first engageable, when said grip-operable member is grip-compressed, with said rockable means to move the same to unlocking position, and subsequently engageable with said sear means to release said firing member for movement to fired position, by one pull on said trigger means.
6. In a firearm, in combination, a frame of said firearm, a main slide movable rearwardly and forwardly on said frame and provided with a rear-face, a breech-block movable with said main slide and movable rearwardly by powder gases and when so moved transmitting rearward movement to said main slide, and comprising a firing pin, a firing member movable to firing position by rearward movement of said main slide and movable to fired position and engageable with said firing pin, rockable means engageable with said rear-face of the main slide to lock the main slide against rearward movement, swinging sear means engageable with said firing member, a grip-operable member engageable with said frame when in position of safety, and releasable from said engagement by grip-compression, means carried by said grip-operable member for moving said rockable means to said locking position when said firing member is moved to firing position, and for moving said sear means to lock said firing member in firing position, means engaging said grip-operable member for blocking said rockable means and sear means in said locking positions, when said grip-operable member is in position of safety and said firing member is in firing position, and movable from said blocking position by grip-compression of the grip-operable member, spring means for moving said firing member to fired position, and affording grip-compression of the grip-operable member, and for returning the grip-operable member to position of safety after grip-compression, trigger means first engageable, when said grip-operable member is grip-compressed, with said rockable means to move the same to unlocking position, and subsequently engageable with said sear means to release said firing member for movement to fired position, by one pull on said trigger means.

firing member is moved to firing position, and for moving said sear means to lock said firing member in firing position, means engaging said grip-operable member for blocking said rockable means and sear means in said locking positions when said grip-operable member is in position of safety, and movable from said blocking position by grip-compression of the grip-operable member, spring means for moving said firing member to fired position, and affording grip-compression of the grip-operable member, and for returning the grip-operable member to position of safety after grip-compression, and trigger means first engageable, when said grip-operable member is grip-compressed, with said rockable means to move the same to unlocking position, and subsequently engageable with said sear means to release said firing member for movement to fired position, by one pull on said trigger means.

7. In a firearm, in combination, a frame of said firearm, a main slide movable rearwardly and forwardly on said frame, and provided with a rear face, a breechblock movable with said main slide and movable rearwardly by powder gases and when so moved transmitting rearward movement to said main slide, and comprising a firing-pin wholly carried by said breechblock, a firing member movable to firing position and to fired position and engageable with said firing pin, rockable means engageable with said rear face of the main slide to lock the main slide against rearward movement, swinging sear means engageable with said firing member, a grip-operable member engageable with said frame when in position of safety, and releasable from said engagement by grip-compression, means carried by said grip-operable member for moving said rockable means to said locking position when said firing member is moved to firing position, and for moving said sear means to lock said firing member in firing position, and for moving said sear means to lock said firing member in firing position, means engaging said grip-operable member for blocking said rockable means and sear means in said locking positions, when said grip-operable member is in position of safety and said firing member is in firing position, and movable from said blocking position by grip-compression of the grip-operable member, spring means for moving said firing member to fired position, and affording grip-compression of the grip-operable member, and for returning the grip-operable member to position of safety after grip-compression, trigger means first engageable, when said grip-operable member is grip-compressed, with said rockable means to move the same to unlocking position, and subsequently engageable with said sear means to release said firing member for movement to fired position, by one pull on said trigger means.

said trigger means, means actuated by said firing member to move said trigger means to prevent interference thereof with said rockable means and swinging sear means 5 when said firing member is moved to firing position, and means for moving said trigger means to normal position when said firing member is moved to firing position.

8. In a firearm, in combination, a frame 10 of said firearm, a main slide movable rearwardly and forwardly on said frame and provided with a rear face, a breechblock movable with said main slide and movable rearwardly by powder gases and when so moved transmitting rearward movement to said main slide, and comprising a firing-pin wholly carried by said breechblock, a firing member movable to firing position by rearward movement of said main slide and movable to fired position and engageable with said firing-pin, rockable means engageable with said rear face of the main slide to lock the main slide against rearward movement, sear means engageable with said firing member, a grip-operable member engageable with said frame when in position of safety, and releasable from said engagement by grip-compression, spring means carried by said grip-operable member for moving said rockable means to said locking position when said firing member is moved to firing position, and moving said sear means to lock said firing member in firing position, means engaging said grip-operable member for 35 blocking said rockable means and sear means in said locking positions when said grip-operable member is in position of safety, and movable from said blocking position by grip-compression of the grip-operable member, spring means for moving said firing member to fired position, and affording grip-compression of the grip-operable member and for returning the grip-operable member to position of safety after grip-compression, and trigger means first engageable, when said grip-operable member is grip-compressed, with said slide-detainer and controller to rock the same downwardly, and subsequently engageable with said sear means to release said firing member for movement to fired position, by one pull on said trigger-member.

10. In a firearm, in combination, a frame of said firearm, comprising a grip-stock, a main slide movable rearwardly and forwardly on said frame and provided with a rear face, means on said main slide for guiding a firing-pin and providing abutment for a firing-pin spring, a breechblock movable with said main slide and movable rearwardly by powder gases and when so moved transmitting rearward movement to said main slide, and comprising a firing-pin engaging said means for guiding, and provided with a firing-pin spring abutting said means for guiding, said firing-pin being wholly carried by said breechblock, a firing member movable to firing position and to fired position, a slide-detainer and controller rockable upwardly and engageable with said rear face of the main slide, means for guiding said slide-detainer and controller in rocking movement and means for limiting upward movement thereof, a swinging sear member engageable with said firing member, a grip-safety member pivotally connected to said grip-stock and engageable with said frame when in position of safety, and releasable from engagement with said frame by grip-compression, an actuator carried by said grip-safety member for rocking said slide-detainer and controller upwardly when said firing member is moved to firing position, an actuator carried by said grip-safety member for mov- 125

9. In a firearm, in combination, a frame of said firearm comprising a grip-stock, a main slide movable rearwardly and forwardly on said frame, and provided with a rear face, a breechblock movable with said main slide and movable rearwardly by powder gases and when so moved transmitting rearward movement to said main slide, and comprising a firing-pin wholly carried by said breechblock, a firing member movable to firing position by rearward movement of said main slide and movable to fired position and engageable with said firing-pin, a slide-detainer and controller rockable upwardly to engage said rear face to lock said main slide against rearward movement, a sear member engageable with said firing member, a grip-safety member pivotally connected to said grip-stock and engageable with said frame when in position of safety, and releasable from engagement with said frame by grip-compression, spring means carried by said grip-safety member for 70 rocking said slide-detainer and controller upwardly when said firing member is moved to firing position, and moving said sear member to lock said firing member in firing position, a blocking member engaging said grip-safety member and engageable with said slide-detainer and controller and engageable with said sear member when said grip-safety member is grip-compressed, spring means for moving said firing member to fired position, and affording grip-compression of the grip-safety member, and for returning the grip-safety member to position of safety after grip-compression, and a trigger member first engageable, when 80 said grip-safety member is grip-compressed, with said slide-detainer and controller to rock the same downwardly, and subsequently engageable with said sear means to release said firing member for movement to 85 fired position, by one pull on said trigger-member.

10. In a firearm, in combination, a frame of said firearm, comprising a grip-stock, a main slide movable rearwardly and forwardly on said frame and provided with a rear face, means on said main slide for guiding a firing-pin and providing abutment for a firing-pin spring, a breechblock movable with said main slide and movable rearwardly by powder gases and when so moved transmitting rearward movement to said main slide, and comprising a firing-pin engaging said means for guiding, and provided with a firing-pin spring abutting said 100 means for guiding, said firing-pin being wholly carried by said breechblock, a firing member movable to firing position and to fired position, a slide-detainer and controller rockable upwardly and engageable with said rear face of the main slide, means for guiding said slide-detainer and controller in rocking movement and means for limiting upward movement thereof, a swinging sear member engageable with said firing member, a grip-safety member pivotally connected to said grip-stock and engageable with said frame when in position of safety, and releasable from engagement with said frame by grip-compression, an 105 actuator carried by said grip-safety member for rocking said slide-detainer and controller upwardly when said firing member is moved to firing position, an actuator carried by said grip-safety member for mov- 110

11. In a firearm, in combination, a frame of said firearm comprising a grip-stock, a main slide movable rearwardly and forwardly on said frame, and provided with a rear face, a breechblock movable with said main slide and movable rearwardly by powder gases and when so moved transmitting rearward movement to said main slide, and comprising a firing-pin wholly carried by said breechblock, a firing member movable to firing position by rearward movement of said main slide and movable to fired position and engageable with said firing-pin, a slide-detainer and controller rockable upwardly to engage said rear face to lock said main slide against rearward movement, a sear member engageable with said firing member, a grip-safety member pivotally connected to said grip-stock and engageable with said frame when in position of safety, and releasable from engagement with said frame by grip-compression, spring means carried by said grip-safety member for 115 rocking said slide-detainer and controller upwardly when said firing member is moved to firing position, and moving said sear member to lock said firing member in firing position, a blocking member engaging said grip-safety member and engageable with said slide-detainer and controller and engageable with said sear member when said grip-safety member is grip-compressed, spring means for moving said firing member to fired position, and affording grip-compression of the grip-safety member, and for returning the grip-safety member to position of safety after grip-compression, and a trigger member first engageable, when 120 said grip-safety member is grip-compressed, with said slide-detainer and controller to rock the same downwardly, and subsequently engageable with said sear means to release said firing member for movement to fired position, by one pull on said trigger-member.

12. In a firearm, in combination, a frame of said firearm comprising a grip-stock, a main slide movable rearwardly and forwardly on said frame, and provided with a rear face, a breechblock movable with said main slide and movable rearwardly by powder gases and when so moved transmitting rearward movement to said main slide, and comprising a firing-pin wholly carried by said breechblock, a firing member movable to firing position by rearward movement of said main slide and movable to fired position and engageable with said firing-pin, a slide-detainer and controller rockable upwardly to engage said rear face to lock said main slide against rearward movement, a sear member engageable with said firing member, a grip-safety member pivotally connected to said grip-stock and engageable with said frame when in position of safety, and releasable from engagement with said frame by grip-compression, an actuator carried by said grip-safety member for rocking said slide-detainer and controller upwardly when said firing member is moved to firing position, an actuator carried by said grip-safety member for mov- 130

ing said sear member to lock said firing member in firing position, a blocking-member comprising adjacently pivoted block-portions, each block-portion being provided 5 with an actuator engaging said grip-safety member and with a front-face and with an upwardly extending end, the front-face of one block-portion being engageable with said sear member and the front-face of the 10 other block-portion being engageable with said slide-detainer and controller when said grip-safety member is in position of safety, means carried by said grip-safety member engaging said upwardly extending ends of 15 the block-portions to move the block-portions concurrently when said grip-safety member is grip-compressed, spring means for moving said firing member to fired position, and affording grip-compression of the 20 grip-safety member, and for returning the grip-safety member to position of safety after grip-compression, an opening in said grip-stock for receiving a trigger member and permitting downward movement of the 25 trigger member therein, a trigger member received in said opening and movable by pull thereon, and provided with an end first engageable, when said grip-safety member is grip-compressed, with said slide-detainer 30 and controller, and subsequently engageable with said sear member, by one pull on said trigger member, a rod pivotally attached at one end to said firing member and engaging at the other end said trigger member to 35 move the trigger member downwardly in said opening when said firing member is moved to fired position, an actuator engaging said trigger member to move the same upwardly in said opening when said firing 40 member is moved to firing position, and means for guiding said rod in its movement and for limiting upward movement of said trigger member.

11. In a firearm, in combination, a frame 45 of said firearm, a main slide movable rearwardly and forwardly on said frame and provided with a rear face, rockable means engageable with said rear face of the main slide to lock the main slide against rearward movement, and grip-operable mechanism comprising means for moving said 50 rockable means to said locking position and means for blocking the same in said locking position, and movable by grip-compression 55 to release said means for blocking.

12. In a firearm, in combination, a frame of said firearm a main slide movable rearwardly and forwardly on said frame and provided with a rear face and comprising a 60 firing-pin, a firing member movable to firing position and to fired position and engageable with said firing-pin, rockable means engageable with said rear face of the main slide to lock the main slide against rearward 65 movement, sear means engageable with said

firing member, and grip-operable mechanism comprising means for moving said rockable means to said locking position when said firing member is moved to firing position and means for moving said sear means 70 to lock said firing member in firing position, and comprising means for blocking said rockable means and sear means in said locking positions, and movable by grip-compression to release said means for blocking. 75

13. In a firearm, in combination, a frame of said firearm, a main slide movable rearwardly and forwardly on said frame and provided with a rear face, a breechblock movable with said main slide and comprising a firing-pin, a firing member movable to firing position by rearward movement of said main slide and movable to fired position and engageable with said firing pin, rockable means engageable with said rear-face of the main slide to lock the main slide against rearward movement, sear means engageable with said firing member, and grip-operable mechanism comprising means for moving said rockable means to said locking position when said firing member is moved to firing position and means for moving said sear means to lock said firing member in firing position, and comprising means for blocking said rockable means and sear means in said locking positions, and movable by grip-compression to release said means for blocking. 80 85 90 95

14. In a firearm, in combination, a frame of said firearm, a main slide movable rearwardly and forwardly on said frame and provided with a rear face, a breechblock movable with said main slide and comprising a firing-pin wholly carried by said breechblock, a firing member movable to firing position by rearward movement of said main slide and movable to fired position and engageable with said firing-pin, rockable means engageable with said rear-face of the main slide to lock the main slide against rearward movement, sear means engageable with said firing member, and grip-operable mechanism comprising means for moving said rockable means to said locking position when said firing member is moved to firing position and means for moving said sear means to lock said firing member in firing position, and comprising means for blocking said rockable means and sear means in said locking positions, and movable by grip-compression to release said means for blocking. 100 105 110 115 120

15. In a firearm, in combination, a frame of said firearm, a main slide movable rearwardly and forwardly on said frame and provided with a rear face, a breechblock movable with said main slide and movable rearwardly by powder gases and when so moved transmitting rearward movement to said main slide, and comprising a firing-pin 125 130

- wholly carried by said breechblock, a firing member movable to firing position by rearward movement of said main slide and movable to fired position and engageable with 5 said firing pin, rockable means engageable with said rear face of the main slide to lock the main slide against rearward movement, sear means engageable with said firing member, and grip-operable mechanism comprising 10 means for moving said rockable means to said locking position when said firing member is moved to firing position and means for moving said sear means to lock said firing member in firing position, and 15 comprising means for blocking said rockable means and sear means in said locking positions, and movable by grip-compression to release said means for blocking. 16. In a firearm, in combination, a frame 20 of said firearm, a main slide movable rearwardly and forwardly on said frame and provided with a rear face and comprising a firing pin, a firing member movable to firing position by rearward movement of 25 said main slide and movable to fired position and engageable with said firing-pin, rockable means engageable with said rear face of the main slide to lock the main slide against rearward movement, a dependent 30 swinging sear member engageable with said firing member to lock the same in firing position, means for moving said rockable means and sear means to said respective locking positions, means for moving 35 said firing member to fired position, and a trigger first engageable with said rockable means for moving the same to release said main slide, and subsequently engageable with the depending end of said swinging 40 sear member for moving the same to release said firing member for movement to fired position, by one pull on said trigger. 17. In a firearm, in combination, a frame 45 of said firearm, a main slide movable rearwardly and forwardly on said frame and provided with a rear face, a breechblock movable with said main slide and comprising a firing-pin, a firing member movable to firing position by rearward movement of 50 said main slide and movable to fired position and engageable with said firing-pin, rockable means engageable with said rear face of the main slide to lock the main slide against rearward movement, a 55 dependent pivotally supported sear member engageable with said firing member to lock the same in firing position, means for moving said rockable means and sear member to said respective locking positions, 60 means for moving said firing member to fired position, and a trigger first engageable with said rockable means for moving the same to release said main slide, and subsequently engageable with the depending end 65 of said sear member for moving the same to release said firing member for movement to fired position, by one pull on said trigger. 18. In a firearm, in combination, a frame of said firearm, a main slide movable rearwardly and forwardly on said frame and provided with a rear face, a breech-block movable with the main slide and movable rearwardly by powder gases prior to rearward movement of said slide and engaging said slide for transmitting initial rearward movement thereto, and comprising a firing pin, the breechblock when moved rearwardly being engageable with said frame and slide for providing retardation of the breechblock relative to the slide while the slide is moved rearwardly and being lockable to the slide for concurrent rearward movement of the slide and breechblock, a firing member movable to firing position by rearward movement of said slide and movable to fired position and engageable with said firing pin, a rockable member engageable with said rear face of the slide to lock the slide against rearward movement, a sear member engageable by swinging movement with said firing member to lock the same in firing position, means for moving said rockable member and sear member to said respective locking positions, means for moving said firing member to fired position, and a trigger member first engageable with said rockable member for moving the same to release said slide, and subsequently engageable with said sear member for moving the same to release said firing member for movement to fired position, by one pull on said trigger member. 19. In a firearm, in combination, a frame of said firearm, a main slide movable rearwardly and forwardly on said frame and provided with a rear face, a breechblock movable with said main slide and movable rearwardly by powder gases prior to rearward movement of said slide and engaging said slide for transmitting initial rearward movement thereto, and comprising a firing pin wholly carried by said breechblock, said breechblock when moved rearwardly being engageable with said frame and slide for providing retardation of the breechblock relative to the slide while the slide is moved rearwardly and being lockable to the slide for concurrent rearward movement of the slide and breechblock, a firing member movable to firing position by rearward movement of said main slide and movable to fired position and engageable with said firing-pin, a rockable member engageable with said rear face of the main slide to lock the main slide against rearward movement, a sear member pivotally supported at a longitudinal end thereof and provided with an oppositely extending longitudinal end and engageable by swinging movement with said firing member to lock the same in firing position. 20. In a firearm, in combination, a frame of said firearm, a main slide movable rearwardly and forwardly on said frame and provided with a rear face, a breechblock movable with said main slide and movable rearwardly by powder gases prior to rearward movement of said slide and engaging said slide for transmitting initial rearward movement thereto, and comprising a firing pin wholly carried by said breechblock, said breechblock when moved rearwardly being engageable with said frame and slide for providing retardation of the breechblock relative to the slide while the slide is moved rearwardly and being lockable to the slide for concurrent rearward movement of the slide and breechblock, a firing member movable to firing position by rearward movement of said main slide and movable to fired position and engageable with said firing-pin, a rockable member engageable with said rear face of the main slide to lock the main slide against rearward movement, a sear member pivotally supported at a longitudinal end thereof and provided with an oppositely extending longitudinal end and engageable by swinging movement with said firing member to lock the same in firing position.

position, means for moving said rockable member and sear member to said respective locking positions, means for moving said firing member to fired position, and a trigger member first engageable with said rockable member for moving the same to release said main slide, and subsequently engageable with said extending longitudinal end

of the sear member for moving the sear member to release said firing member for movement to fired position, by one pull on said trigger member.
